PRINTING TYPE SPACER OR THE LIKE

Frank J. Lemieux, Rumford, R. I.

Application July 6, 1937, Serial No. 152,032

11 Claims. (Cl. 101—398)

This invention relates to printing and particularly to certain of the printing units, lines of which may cooperate with each other or with the slug, spacer or rule as made by the machine of my prior Patent No. 2,007,301 of July 9, 1935, which slug, spacer or rule is also claimed specifically herein.

One of the objects of this invention is to prevent spacers located between words or letters in the line of type or slugs between the lines of type from rising during the printing operation to receive ink and themselves print upon the paper.

Another object of the invention is the formation of type or spacers between type in the line of the type so as to cooperate with other type or spacers between the lines of type to prevent any of the units from dropping out of the form of type when they are bound together in working position.

Another object of the invention is the provision of spacers to be located between the lines of type which will have recesses or grooves to collect oil or lubricant therein that any lint or dust will be collected in the grooves rather than upon the working face of the spacer.

A further object of the invention is to provide an interlock between the unit parts of a form of set-up mono-type so as to better maintain the same in working position.

With these and other objects in view, the invention consists of certain novel features of construction, as will be more fully described, and particularly pointed out in the appended claims.

In the accompanying drawing:

Fig. 1 is a perspective view of a plurality of type units with spacers on either side of the line of type set up in this manner;

Fig. 2 is a perspective view of a type unit carrying a printing character;

Fig. 3 is a perspective view of the unit of Fig. 2 looking at the other side thereof;

Fig. 4 is a perspective view of a type unit to act as a spacer between printing characters;

Fig. 5 is a perspective view of a unit of Fig. 4 looking at the other side thereof;

Fig. 6 is an enlarged perspective view of a corner of a type unit illustrating the barb or spur thereon and showing the unit as of the smallest point type;

Fig. 7 is a perspective view of a slug to be located between the lines of type;

Fig. 8 is a perspective view of a slug of a little different construction being grooved on both sides instead of one side;

Fig. 9 is a perspective view of the slug shown in Fig. 8 looking at the opposite side thereof;

Fig. 10 is an end view of two lines of type with spacers, or slugs located between the lines and at either side thereof;

Fig. 11 is a view similar to Fig. 10 but illustrating the relative positions in two lines of type of a spacer unit and character-carrying unit;

Fig. 12 is an end view of three lines of type showing the relative position of a spacer between two type heads in the middle row and with slugs between each of the lines or rows of type and at either side thereof;

Fig. 13 is an end view of a plurality of lines of type one line in contact with the other and without any slug or spacer such as shown in Figs. 10 and 11 between the lines.

In the setting of mono-type into forms for printing purposes frequently after the type is set up on the stone and bound together for transfer if there be any irregularities in the formation of the type as cast, this type if small may itself fall from its position in the bound block, or if irregular or too large may cause other units to drop from position. Also, spacers which are positioned between character printing units in a line of type often work upwardly so as to receive ink and print upon the paper or surface with which the type contacts; and in order to avoid both of these faults I have provided a barb or spur opposite the usual indicating groove in the type and at substantially the same distance from the foot of the type or spacer that the groove is located, so as to enter the groove of a previously formed line of type and prevent vertical movement of any individual unit type either upwardly or downwardly; and the grooved slug which is located between the lines of type and which may be made by the machine illustrated in my Patent No. 2,007,301, cooperates with this new form of units in that its groove is so located as to be substantially the same distance from the foot of the slug as the groove in the type, whereby a spur on the type units will enter this recess and lock the parts against vertical movement, thus making a unit assembly of an improved character; and the following is a more detailed description of the present embodiment of this invention, illustrating the preferred means by which these advantageous results may be accomplished:

By the term "type unit" I intend to include either a character-carrying unit, as shown in Fig. 2, a unit intended for spacing such character-carrying units such as shown in Fig. 4 or 5, a slug or spacer for spacing lines of such units,

such as shown in Figs. 7, 8 or 9, or a rule for printing a line.

With reference to the drawing, 10 designates a type unit which is cast in a rectangular solid block shape with a letter or character 11 on the head end 12 thereof, there being a foot portion 13, side walls 14, an end wall 15 which is grooved as at 16 to designate the lower edge of the letter as is customary in type casting, and an opposite end wall 17 which is provided with a barb or spur 18 which is the same distance from the foot 13 as is the groove 16 and is adapted to enter the groove 16 of a line of type which may come adjacent thereto, as shown in Fig. 13.

15 The type unit for spacing character units is designated generally 19 and is illustrated in Figs. 4 and 5. It is similar in all respects to the character-carrying unit 10 except that it is a different height from its foot 20, its top wall 21 being substantially below the head of the type 10 and being plain. This spacer has side walls 22, an end wall 23 provided with a groove 24 the same distance from the foot 20 as is the groove 16 from the foot 13. The opposite end wall of 25 this spacer is provided with a barb or spur 26 which is located the same distance from the foot 20 as is the groove 24 in its opposite end wall.

The barb or spur 18 or 26 extends pointwise of the type and is of a horizontal length slightly less setwise than the smallest point of type which is provided and is arcuate in shape, as illustrated at 27 in Fig. 6. By the term "pointwise" I mean the direction in which the measurement is taken to determine the point of the type that is the 30 width of the body of the type unit in the direction of the depth of a column on a printed page and is the distance between the two spacers 30 in Fig. 1. By the term "setwise" I mean the direction lengthwise along the spacers 30 in Fig. 1 or from 35 left to right along a printed page. The rather small dimension of this spur is particularly desirable so that the unit may be withdrawn from the form of type set up with a small spreading of the lines of type or slugs on either side of the line in 40 which the unit to be withdrawn is located.

The slugs which are positioned between the lines or rows of type are designated generally 30 and comprise an extruded length of alloy metal of any desired thickness with flat opposite surfaces 31 and 32 with a groove 33 extending longitudinally of the surface 32 and located midway thereof which will be substantially the same distance from either its top or bottom as is the groove 16 or 24 from the foot of the character 45 or spacer unit. It is also desirable in many instances to provide in addition to the groove 33 grooves 34 and 35 at the opposite surface of the slug or extruded ribbon 30. These grooves have an advantage in that if several of the spacers be 50 positioned face to face in a bundle or group they may be more easily and quickly picked apart than were the grooves not present therein. These grooves also have the advantageous feature of accumulating such oil as may be present on their 55 surfaces so that any fine particles of grit or the like will accumulate in these oil collected portions rather than upon the working faces 31 or 32 of the spacer. The groove 33, as will be evident in Figs. 10, 11 and 12, is in such position as to receive the barb or spur 18 of the type so as to prevent the type from dropping from a bound up 60 form of a plurality of units of mono-type, should one of the units be slightly smaller than the other, or larger than its neighbor and thus not 65 receive equal binding pressure. Also, as shown 70

in Fig. 11, the spacer 19 is shown as located with its barb or spur 26 located in the groove 33 so that it cannot move any substantial distance vertically in either direction and thus cannot rise to become flush with the character 11 and receive ink and deposit the ink upon the printing surface.

In instances where no slugs are provided between the rows or lines of assembled units the spurs or projections 18 or 26 will extend into the 10 recesses or grooves 16 or 24 of adjacent rows or lines of type units so as to interlock therewith and provide the desired interlocking connection against vertical movement of the units.

The foregoing description is directed solely towards the construction illustrated, but I desire it to be understood that I reserve the privilege of resorting to all the mechanical changes to which the device is susceptible, the invention being defined and limited only by the terms of the ap- 15 20 pended claims.

I claim:

1. A type unit comprising a block-like body having vertical walls extending upwardly from its foot with the walls which engage the next unit 25 on the same line of type smooth, the wall extending from the lower edge of the letter provided with a groove and the wall extending from the upper edge of the letter provided with a spur and extending but a portion of the distance across the 30 wall and tapered to merge into the wall from which it extends.

2. A type unit comprising a block-like body having vertical walls extending upwardly from its foot with the walls which engage the next body 35 on the same line of type smooth, the wall extending from the lower edge of the letter provided with a groove and the wall extending from the upper edge of the letter provided with a spur at substantially the same distance from the foot 40 of the body as said groove, said spur extending but a portion of the distance across the wall and tapered to merge into the wall from which it extends.

3. A type unit comprising a block-like body 45 having a spur extending pointwise from one of the side walls thereof, said spur tapering and extending a greater distance beyond said side wall at one point along its extent setwise than another.

4. A type unit comprising a block-like rectangular body having vertical side walls extending upwardly from its foot and a spur extending pointwise outwardly from one of the walls at one edge, said spur tapering with its greatest 55 distance beyond said side wall being located at said edge thereof.

5. A type unit comprising a block-like body having a spur extending pointwise from one of the side walls thereof and tapering setwise to 60 merge into the side wall beyond which it extends.

6. A type unit comprising a block-like rectangular body having vertical side walls extending upwardly from its foot, and a groove in one surface thereof, and a spur extending from an opposite surface thereof at the same distance from said foot as said groove, said spur tapering and extending a greater distance beyond said side wall at one point along its extent setwise than 70 another.

7. A system of type having a plurality of units varying in setwise thickness, each comprising a block-like body, each of the units of narrowest setwise thickness being provided with spurs ex- 75

tending pointwise from one of the side walls thereof, the spurs on any unit of the system being of a length no greater than the setwise thickness of the narrowest unit of the system.

5 8. A system of type having a plurality of units varying in setwise thickness, each comprising a block-like body with a spur extending pointwise from one of the side walls thereof, the spurs on all units of the system being of equal length regardless of setwise thickness and of a length no greater than the setwise thickness of the narrowest unit of the system.

10 9. A system of type having a plurality of units varying in setwise thickness, each comprising a block-like body with a tapered spur extending pointwise from one of the side walls thereof, the spurs on all units of the system being of equal length regardless of setwise thickness and of a length no greater than the setwise thickness of the narrowest unit of the system.

15 20

10. A system of type having a plurality of units varying in setwise thickness, each comprising a block-like body with a tapered spur extending pointwise from one of the side walls thereof, the spurs on all units of the system being of equal length regardless of setwise thickness and of a length no greater than the setwise thickness of the narrowest unit of the system, each of said tapered spurs merging into the side wall beyond which it extends.

5 11. In combination, rows of type units, spacers between said rows of units each provided with a longitudinally extending recess, and spurs on the side walls of some of said type units at a location to extend into the recess in said spacer, each 15 of said spurs being tapered to extend a greater distance beyond said side wall at one point along its extent setwise than at another.
